UNITED STATES PATENT OFFICE.

ERASTUS E. WINKLEY, OF LYNN, MASSACHUSETTS.

STEERING APPARATUS.

1,330,418.

Specification of Letters Patent. Patented Feb. 10, 1920.

Application filed December 27, 1915. Serial No. 68,855.

To all whom it may concern:

Be it known that I, ERASTUS E. WINKLEY, a citizen of the United States, residing at Lynn, in the county of Essex and State of Massachusetts, have invented certain new and useful Improvements in Steering Apparatus; and I do hereby declare the following to be a full, clear, and exact description of the invention, such as will enable others skilled in the art to which it appertains to make and use the same.

The present invention relates to an improvement in steering apparatus.

One object of the invention is to produce an improved steering apparatus having provision whereby a predetermined course consisting of one or more legs may be laid out for the dirigible moving object, such as a vessel, torpedo, flying machine or the like, to which the apparatus may be applied, and when the object has completed one leg of the predetermined course, it will be automatically headed on the next leg. A further object of the invention is to produce a steering apparatus having improved and simplified means for automatically restoring the moving object to the direction in which it was proceeding upon a deviation therefrom.

To the accomplishment of these objects, one feature of the invention consists in an improved course-setting mechanism whereby any predetermined course consisting of one or more legs may be laid out for the moving object. Related to this feature of the invention is the feature for detecting the amount the moving object deviates from the direction the object should proceed in. The means for detecting the amount of deviation from its given direction in the present invention depends upon the principle of the magnetic needle, that is, upon something which will maintain a constant direction irrespective of the movements of the object on which it is placed. It is obvious, of course, that instead of a magnetic needle a gyroscope or a selenium cell may be employed in connection with the mechanism for detecting the deviation of the object from its given course. Controlled by these mechanisms is the guiding device actuating means which operates first, to direct the object in whatever direction it is desired it should proceed, and second, to restore the object to the course in which it was proceeding upon deviation therefrom.

Other features of the present invention consist in certain novel mechanical devices, and in certain novel arrangements and combinations of parts, the advantages of which will be apparent to those skilled in the art.

The principle and mode of operation of the invention will be understood from the following description taken in conjunction with an inspection of the accompanying drawings of the preferred form of the invention, in which Figure 1 is a plan of the improved steering apparatus; Figs. 2, 3, and 4 are sectional elevations taken on the lines 2—2, 3—3, and 4—4 respectively, of Fig. 1; Fig. 5 is an enlarged plan of the mechanism with its associated parts, for detecting the amount the vessel deviates from its given course; Fig. 6 is an enlarged plan, partly in section, of one of the locking devices; Fig. 7 is a detail of part of the mechanism for actuating the stopping device; Figs. 8 and 9 are enlarged side elevations, partly in section, of part of the apparatus shown in Fig. 1; Fig. 10 is the layout of a predetermined course; Fig. 11 is the layout of the course-setting wheel showing the relative sizes of the course pins used in heading the vessel in the direction of the legs of the predetermined course laid out in Fig. 10; and Fig. 12 shows the relative positions of the gage and gage feeler while the vessel is headed on the predetermined course laid out in Fig. 10.

Course-setting mechanism.

The steering apparatus shown in the illustration of a specific embodiment of the invention comprises means for determining or setting the course of the vessel or other object to which the steering apparatus may be applied, whether this course consists of a single leg, or of more than one leg, means for detecting the amount the vessel or object deviates from the chosen course, means governed as to its operative position by the two first named means for controlling the amount of movement to be imparted to the guiding device or rudder for heading the vessel on or for restoring the vessel to its chosen course, means for actuating the rudder, and other mechanisms incidental to the operation of the above-named mechanisms. The word "vessel" will hereinafter in the descriptive matter be used for designating the moving object, the course of which is governed by the steering apparatus. The

means for determining or setting the course it is desired the vessel should pursue comprises a course-setting wheel 1 (Figs. 1 and 3) removably mounted on a shaft 2 journaled 3 in a support 3 rising from a platform 4 upon which the steering apparatus is supported. The wheel 1 is provided on the lateral edge 5 of its rim 6 with a series of holes of uniform depth adapted to receive 10 a series of course-setting pins 7 and 8. The heads of these course-setting pins are adapted to be engaged by a course pin feeler 9 which constitutes one arm of a three-armed bellcrank lever 10 fulcrumed on a 15 support rising from the platform 4. The lengths of these course-setting pins are determined by the direction in which the vessel is to sail. When either the shortest pins 7 or the longest pins 8 are engaged by the 20 course pin feeler 9, the vessel pursues a course in the same direction, and when other pins intermediate in length between the shortest and the longest pins are in operative position and are engaged by the 25 course pin feeler, the vessel pursues a course differing angularly from the course the vessel pursues when the shortest or the longest pins are in operative position, proportionately to the position these intermediate pins 30 occupy between the heads of the shortest and the longest pins. The course pin feeler 9 is adapted to be brought into contact with and to be disengaged from the course-setting pins at intervals. These intervals may 35 be varied according to the conditions under which the vessel is to sail. The course pin feeling movements are imparted to the feeler 9 by a spring 11, and the movements for disengaging the feeler 9 from the course 40 pins are imparted by a cam 12 which engages a cam roll 13 carried by an arm 14 of the bellcrank lever 10. The cam 12 is mounted on a cam shaft 15 journaled in supports 16 and 17 rising from the platform 4. The cam shaft 15 receives its actuation from the propeller shaft 18 through a chain of gearing, hereinafter to be more specifically described. The active part of the cam 12 rises and falls abruptly in order 45 to give quick course pin engaging and disengaging movements to the feeler 9. When the feeler 9 has engaged one pin a predetermined number of times, the course-setting wheel 1 is turned on the shaft 2 so as 50 to present the head of the next pin for feeling movements by the feeler 9. The course-setting wheel is rotated by means of a ratchet wheel 20 removably mounted on the shaft 2. The ratchet wheel 20 is 55 provided on its periphery with a series of teeth or notches 21 adapted to be engaged by a pawl 22. Motion is communicated to the pawl 22 from the cam shaft 15, and for this reason a pinion gear 24 is mounted on 60 one end of the cam shaft 15 and meshes 65 with a cam driving gear 25. The gear 25 drives a cam 26, and both are mounted on a stud shaft 27. A peripheral cam surface 28 is cut on one side of the cam 26 and is adapted to be engaged by a cam roll 29 70 carried on the upper end of a lever 30 fulcrumed on a pin 31 journaled in a support on the platform 4. A suitably connected spring 32 holds the roll 29 in engagement with the cam surface 28. One end of a 75 pawl link 33 is pivotally connected with the cam roll 29 and its other end is pivoted on a pawl supporting pin 34 secured to the upper end of a pawl lever 35 fulcrumed on the shaft 2. 80

Deviation detecting means.

The means for detecting the amount the vessel deviates from the chosen or predetermined course comprises a compass, a 85 gage device and a gage feeler. The compass is of usual construction and comprises a compass card 37 secured to a compass needle freely pivoted in the usual manner in a compass bowl 38 which is supported in an 90 outer gimbal ring 39 and an inner gimbal ring 40. The outer gimbal ring 39 is journaled in supports 41 and 42 rising from the platform, and the inner gimbal ring 40 is journaled in bearings 43 and 44 formed in 95 the outer gimbal ring.

The gage device consists of a spirally formed gage 45 secured to the compass card 37 for movement with the compass needle. The gage is of such construction that, when 100 either the point 46 or the point 47 thereon is contacted with by the gage feeler, the vessel will pursue a course in the same direction. When the point 46 on the spiral gage is contacted with by the gage feeler, the 105 shortest course-setting pins 7 are engaged by the course pin feeler 9; and when the point 47 on the spiral gage is contacted with by the gage feeler, the longest course-setting pins 8 are engaged by the feeler 9. The 110 position of the spiral gage device shown in Fig. 1 is arbitrarily chosen for purposes of illustration, it being obvious that the gage device may be so positioned relatively to the points on the compass card that when 115 either the point 46 or the point 47 is contacted with by the gage feeler, the vessel will pursue a course either due south, west, or east respectively. The increase in the 120 curve of the spiral gage for each degree is uniform, so that the increase in the curve between the point 47 and the point 48, angularly removed from the point 47 by 90° , is one-fourth of the distance between the points 47 and 46. So also, the increase of 125 the curve at the points 49 and 50, which are removed angularly from the point 47 by 180° and 270° respectively, is one-half and three-fourths respectively, of the distance between the points 47 and 46. The distance 130

between the points 46 and 47 corresponds to the difference in length between the shortest and longest course pins.

The gage feeler 52 is slidably mounted in 5 the compass gimbals for movement toward and from the gage device. The outer end of the gage feeler 52 is pivotally mounted on the free end of an arm 53 of a bellcrank lever 54 fulcrumed on a bracket 55 projecting laterally from the compass bowl 38. Movement toward the gage device is imparted to the gage feeler 52 by a spring 57, one end of which is connected with the support 42 and the other end of which is connected with the arm 53 of the bellcrank lever 54. Movement from the gage device is imparted to the gage feeler 52 by the engagement of a pawl 58 with one of the teeth 59, 60, 61, 62, or 63, of a rack 64 secured to or 20 made integral with an arm 66 of the bellcrank 54. When the point 46 is contacted with by the gage feeler 52, the pawl 58 engages the tooth 63; and when the point 47 is contacted with by the gage feeler, the 25 pawl 58 engages the tooth 59. The distance between the teeth of the rack 64 corresponds to the increase of the curve of the spiral gage for every 90° , and to one-fourth of the distance between the shortest and longest 30 course-setting pins. The pawl 58 is pivotally mounted on a lever 68 fulcrumed at 69 on a support rising from the platform. The lever 68 is actuated by the engagement of a cam 70 mounted on the cam shaft 15, with 35 a cam roll 71 carried by the lever 68. The cam roll 71 travels in a groove in the cam 70 of such form that the period of disengagement of the gage feeler 52 from contact with the gage 45 is longer than the period 40 of engagement. The gage feeler 52 has a gage feeling movement corresponding to every course pin feeling movement of the course pin feeler 9. During the gage feeling movements of the gage feeler 52, the 45 pawl 58 is held out of engagement with the teeth of the rack 64 by means of a shield 72 to permit the rack to swing past the pawl.

When the gage feeler 52 is in contact with the spiral gage 45, the compass card is locked, in order to prevent injury to the pivotal mounting of the compass needle, by the pressure of the gage feeler 52 against the gage. Since this mechanism forms no part of and is not necessary to a disclosure of the present invention, it is not illustrated. Its construction and mode of operation are disclosed and claimed in United States Letters Patent No. 1,200,288, granted to me October 3, 1916.

80 *Rudder controlling mechanism.*

The means for controlling the amount of movement to be imparted to the guiding device or rudder for directing the vessel on or 65 restoring the vessel to its predetermined

course comprise a rudder controller 74 and a controller rod 75. The rudder controller 74 is provided with an arcuate controller rod feeling face or surface 76 and is pivoted on a roll 77 carried on the outer end of a lever 78 fulcrumed at 79 on a support rising from the platform. The roll 77 is engaged for movement by a collared sleeve 80. Each time that the course pin feeler 9 and the gage feeler 52 perform their feeling functions, the rudder controller 74 is swung on its pivot away from the controller rod; and for this purpose the controller 74 is connected with an arm 81 of the bellcrank 10 by means of a link 82 pivoted to the free 80 end of the arm 81 and to the controller 74 at 83. The controller rod 75 is secured to an elongation of a collared sleeve 85 which engages a roll 86 carried by the free end of the arm 66 of the bellcrank lever 54. The 85 collar 85 and its elongated part 87 are mounted for sliding movements on an extension of the gimbal trunnion journaled in the bearing 42 (Fig. 8). A bearing 88 supports the outer end of the part 87. When 90 the cam 70 actuates the lever 68 to move the gage feeler 52 away from the gage 45, the controller rod 75 moves to the left toward the compass; and when the spring 57 moves the gage feeler 52 toward the gage, the 95 controller rod 75 moves toward the right away from the compass. When the cam 70 moves the lever 68 to disengage the pawl 58 from one of the teeth of the rack 60 to permit the spring 57 to move the gage feeler 52 into 100 contact with the gage and the controller rod 75 has thereby been moved into operative position, the rudder controller 74 is adapted to move until its arcuate face 76 comes into engagement with the end of the controller 105 rod 75. At the time the rudder controller is swung on its pivot away from the controller rod 75, it is immediately thereafter or simultaneously therewith moved to the right, that is, in a direction away from the 110 controller rod. When the rudder controller swings back again, the course pin feeler 9 engages one of the course-setting pins. If during the time the gage feeler 52 is disengaged from the spiral gage, the vessel does 115 not deviate from its predetermined course, when the feeler 52 is again in contact with the gage, the controller rod 75 will be returned to its normal position, the course pin feeler 9 will contact with one of the heads 120 of the course pins, and the same point on the arcuate surface 76 of the rudder controller 74 will come into contact with the controller rod 75. After the controller 74 has been turned on its pivot by the spring 125 11, when the spring 11 acts to bring the feeler 9 into engagement with a course pin, a spring 89 acts to move the controller into contact with the controller rod 75. If during the disengagement of the feeler 52 from 130

the spiral gage 45 the vessel swings to the right, by the time the controller 74 is again returned to its feeling position, the controller rod 75 will have been moved farther 5 to the right away from the compass, and, consequently, the controller will be positioned to the right of its normal position.

But if, during the disengagement of the feeler 52 from the gage 45 the vessel swings 10 to the left, by the time the controller 74 is again in feeling position, the rod 75 will occupy a position farther to the left toward the compass and so, the controller will be positioned to the left of its normal position. 15 The operative position of the controller rod 75 is governed by the gage feeling position of the gage feeler 52; and according to the position of the controller rod 75, the controller 74 governs the direction of movement 20 to be imparted to the rudder to restore the vessel to its given course.

Rudder actuating mechanism.

The mechanism for imparting movement 25 to the rudder to turn it in a direction to head the vessel on or to restore the vessel to its given course comprises a rudder actuating cam 90 secured to a jack shaft 91 mounted for sliding and rotative movements in a bearing 93 in a support on the platform. Another jack shaft 92 is mounted for rotative movements in a support 94. The shaft 92 is geared to the propeller shaft 18 for actuation thereby, and the shaft 91 is rotated 30 by the shaft 92 by a pin and slot connection consisting of a flange 95 secured to the shaft 92 having a slot adapted to receive a pin 96 projecting laterally from a collared sleeve 97 secured to the shaft 91. The left-hand 35 end of the shaft 92 is reduced in diameter and is adapted to project into a bore in the right-hand end of the shaft 91, so that the shaft 91 may slide thereon (Fig. 9). The collared sleeve 80 which engages the roll 77 40 to which the controller 74 is pivoted, is secured to one end of the shaft 91; and the construction of the shaft 91 and the parts carried by it is such that when movement in either direction is transmitted to the sleeve 45 80 or to the sleeve 97, the shaft 91, the cam 90, and both sleeves are moved laterally to the right or left toward or away from the compass according to the direction of the transmitting force. The cam 90 is in the 50 form of a collared sleeve and is provided with two oppositely disposed, inwardly projecting cam surfaces 99 and 100 which are, respectively, adapted to engage a cam roll 101 carried by a lever 102 pivoted at 103 on 55 a support on the platform. When the cam 90 occupies the position shown in Fig. 1, the cam surfaces 99 and 100 do not engage the cam roll 101 as the cam rotates. This position of the cam is called its inoperative 60 or neutral position and is the position it occupies when the vessel is headed on its pre-determined course. When the cam 90 is at the right of its normal position,—which is the case when the vessel deviates to the right of its course or is to be turned to the left,—the cam surface 99 engages the cam roll 101 and turns the lever 102 on its pivot to communicate a clockwise movement to the rudder 104. And, when the cam is to the left of its normal position,—which is the case when the vessel 70 deviates to the left of its course or is to be turned to the right,—the cam surface 100 engages the cam roll 101 and swings the lever 102 to communicate an anti-clockwise movement to the rudder. The rudder 104 is shown out of its true position relative to the other parts of the steering mechanism for purposes of illustration. The connections between the rudder actuating lever 102 and the rudder comprise a link 105 pivoted to the lever 102 at 106 and to an arm 107 secured to the rudder post.

The rudder 104 is turned to the full extent of its course directing or course restoring position by a single actuation of the lever 102, and is returned to its normal position in alignment with the course of the vessel by successive increments of return movements. It is obvious that the rudder will not remain to the full extent of its course 90 directing or course restoring position until the vessel has been completely restored to its predetermined course; but immediately the vessel responds to the action of the rudder and its head swings either to the left or to the right, the gage feeler 52 will engage a point on the spiral gage at a lesser or greater distance from the center of the gage, so that the mechanism between the gage and the rudder will act to return the rudder to its 95 normal position as soon as the vessel has responded to the action of the rudder. And the rudder will be restored gradually and progressively to its normal position proportionately to the swing of the vessel into the 100 predetermined course.

Locking device for rudder actuating mechanism.

The lever 102 is locked against movement 115 at all times, except when the cam surfaces 99 and 100 are brought opposite the cam roll 101 by the rotation of the cam 90, at which time the lever 102 is unlocked to permit the cam surfaces 99 and 100 to actuate it. The 120 means for locking the lever 102 consists of a locking device 109 (Fig. 6) comprising a casing within which is a recess adjacent the arcuate surface 110 of the lever 102. This recess consists of two compartments having 125 converging rear walls 111 and 112, the arcuate surface 110 forming the front converging walls of the compartments. Within these compartments are received two locking balls 113 and 114. When these balls are in 130

normal position, they are spring pressed toward the narrow ends of their respective compartments so that each engages the arcuate surface 110 of the lever 102 and the rear walls 111 and 112 respectively. When the 5 balls are in this position, if a force is applied to move the lever 102 to the left, viewing Fig. 6, the ball 114 will be jammed between the arcuate surface 110 and the wall 112, thereby holding the lever against movement. So, in like manner, if a force be exerted to move the lever 102 toward the right, the ball 113 will be jammed between the arcuate surface 110 and the wall 111, thereby 10 preventing the lever from moving. A plunger 115 received slidably within the casing and having a beveled head 116, is disposed midway between the balls. When the plunger 115 is moved against the balls, the balls 20 are forced against their springs into the wider ends of their respective compartments, thereby disengaging them from the arcuate surface 110 to permit freedom of movement to the lever 102.

25 The locking device 109 is unlocked at the proper intervals by means of a cam 117 (Figs. 1 and 3) having a circumferential active part which engages a cam roll 118 carried by one arm of a bellcrank lever 119 fulcrumed in a support on the platform. The other arm of the lever 119 engages a rod 120 mounted for sliding movements in a support 121 and in a bracket 122 projecting laterally from the locking device 109.

30 An arm 123 secured to the rod 120 is positively connected with the plunger 115 by means of a collar 124 which receives the end thrust of a compression spring 125, the rear end of which takes against a bearing 126 formed in a bracket on the platform. When 35 the lever 102 is to be unlocked, the active portion of the cam 117 engages the cam roll 118 and moves the rod 120 to compress the spring 125 and push the plunger 115 away from the arcuate surface 110 of the lever 102. In its 40 movement away from the arcuate surface 110, the plunger 115 forces the locking balls to move laterally until they are clear of the arcuate surface 110. When the active part 45 of the cam 117 is disengaged from the roll 118, the compression of the spring 125 forces the plunger 115 toward the arcuate surface 110, thereby permitting the balls 113 and 114 to come into position to hold the lever 50 102 against movement in either direction.

55 As the plunger 115 moves toward the surface 110, the roll 118 is forced against the idle portion of the cam 117 by the movement of the rod 120. The collar 124 is 60 pressed against the rear end of the casing which serves as a stop to prevent the plunger from contacting with the arcuate surface 110.

65 Sliding movements to the left, toward the compass, are imparted to the jack shaft 91

by the spring 89, and to the right, away from the compass, by a roll 128 which is engaged by the collared sleeve 97. The roll 128 is carried on the end of an arm of a bell crank lever 130 fulcrumed on a support rising from the platform 4. The lever 130 is actuated by a cam 132 mounted on the cam shaft 15. The cam 132 engages a cam roll 133 carried by an arm of the lever 130. After the cam 132 has acted to slide the 70 jack shaft 91, and so the controller 74, to the right, thereby permitting a different part of the arcuate surface of the controller to contact with the controller rod, if in the meantime the vessel has deviated from her course, and the controller has been returned into engagement with its rod, the jack shaft 91 is locked against movement in either direction. The jack shaft is locked so that, if the vessel did deviate, and consequently a different portion of the arcuate face of the controller contacts with the controller rod 75 and the cam 90 is to the left or right of its normal position, either the cam surface 99 or the cam surface 100 will be enabled to actuate the lever 102. This locking of the jack shaft 91 occurs just before either the cam surface 99 or 100 moves opposite the roll 101. The means for locking the jack shaft consists of a locking device 135, 80 similar in all respects to the locking device 109. The locking device 135 is locked and unlocked by a cam 137 mounted on the cam shaft 15. The active part of the cam 137 engages a cam roll 138 carried by a lever 139 fulcrumed on a support rising from the platform. The other arm of the lever 139 carries a cam roll 140 which is engaged by a collar on the locking device 135.

Power application.

105

The jack shaft 91-92 and the cam shaft 15 are rotated synchronously by a gear 144 mounted on an extension 145 of the part 92 of the jack shaft. The outer end of the extension 145 is journaled in a bearing 146 supported by a frame 147 (Fig. 4) rising from the platform 4. On the cam shaft 15 is a gear 148 which meshes with a gear 149 of equal size mounted on the extension shaft 110 145. The gear 144 is driven by a pinion gear 151 mounted on a shaft 152 journaled in bearings 153 and 154. The shaft 152 is driven by a worm gear 155 which is engaged by a worm 156 mounted on a shaft 158 journaled for support in bearings 159 and 160. The shaft 158 is rotated by a large worm gear 162 driven by a worm 163 secured to the propeller shaft 18. The size and arrangement of the gears between the propeller shaft 18 and the various parts of the steering apparatus are such that the jack shaft 91-92 and the cam shaft 15 are rotated once each thirty seconds (it being assumed 115 that the propeller shaft makes 1200 revolu- 120 125 130

tions per minute), so that the feeling movements of the course pin feeler 9, the rudder controller 74, and the gage feeler 52, are performed once every thirty seconds. The size and arrangement of the gears between the cam shaft 15 and the ratchet wheel 20 are such that the ratchet wheel 20 and the course-setting wheel 1 are actuated through an angle equal to the angular distance between the ratchet teeth 21, once every six minutes, so that each course-setting pin is contacted with by the feeler 9 twelve times. If the propeller shaft 18 makes less than 1200 revolutions per minute, the parts of the steering apparatus actuated thereby will perform their function correspondingly slower; and if the propeller shaft makes more than 1200 revolutions per minute, the parts of the steering apparatus will perform their functions correspondingly faster. The gears between the various mechanisms comprising the steering apparatus and the propeller shaft may be of any desired size and may be arranged in any desired manner so that the mechanisms will perform their functions at any predetermined intervals. This method of actuating the parts of the steering apparatus from the propeller shaft possesses an advantage over actuating the steering apparatus by clock-work. If a clock is employed, the mechanisms comprising the steering apparatus will perform their functions at stated intervals regardless of the speed of the vessel, and, consequently, if the vessel is proceeding at a slower rate than usual it will be headed on the next leg of its course prematurely. The present arrangement automatically prevents such contingency.

40   *Course restoring operation.*

The cam 12 at each rotation acts to swing the course pin feeler 9 clear of the course pins. This clearance movement of the course pin feeler 9 after each feeling movement is sufficient to permit the feeler to be disengaged from one of the shortest course pins and to engage one of the longest course pins, if need be, on its next feeling movement. Simultaneously with the disengagement of the course pin feeler 9 from a course pin, the rudder controller 74 is swung into position preparatory for a fresh feeling movement. The clearance swing of the rudder controller 55 is sufficient to permit the controller rod 75 to move to the limit of its rightward movement. Substantially simultaneous with the swing of the rudder controller 74 on its pivot, the cam surfaces 99 and 100 rotate 60 beyond the cam roll 101, and the cam 137 acts to unlock the locking device 135. By this time the active part of the cam 132 has engaged the cam roll 133 and swung the lever 130 on its pivot, thereby moving the collar 97 to the right away from the compass

and with it the cam 90 and the collar 80. During these movements the cam 70 has acted to disengage the pawl 58 from one of the teeth of the rack 64 to permit the gage feeler 52 to come into contact with the gage 45. Coincident with the gage feeling movement of the feeler 52, the controller rod 75 comes into operative position as determined by the part of the gage contacted with by the feeler 52. When the controller rod 75 becomes established in its operative position, the active part of the cam 132 passes the cam roll 133, thereby allowing the spring 89 to draw the controller 74 and the cam 90 toward the compass until the controller comes into engagement with the end of the controller rod 75. If during the time that the feeler 52 was in its non-feeling position the vessel did not deviate from its chosen course, the controller rod 75 will be returned to normal position. In this case, the spring 89 will act to return the controller 74 and the cam 90 to their normal positions. Immediately following the return of the controller 74 to its feeling position and after the cam 90 has assumed its return position as determined by the controller, the locking device 135 acts to lock the lever 130. The locking of the lever 130 by the locking device 135 holds the cam 90 and the part 91 of the jack shaft against lateral movement in operative position. During the movements just described, the locking device 109 has held the lever 102 and the rudder 104 stationary. Immediately after the cam 90 and the shaft 91 have been locked against lateral movement by the locking device 135, the locking device 109 acts to unlock the lever 102; and simultaneously with the unlocking of the lever 102 the forward ends of the cam surfaces 99 and 100 are brought opposite the cam roll 101 by the rotation of the cam 90. The locking of the shaft 91 against lateral movement locks the controller 74 in its feeling position. This allows the cam 70 to actuate the pawl 58 to move the feeler 52 clear of the gage 45 to permit the vessel to move relatively to the compass card. As the pawl 58 swings the bellcrank 54 to free the feeler 52 from the gage 45, it moves the controller rod 75 to the left out of contact with the controller 74.

If the vessel deviates to the right of its course, thereby causing the feeler 52 to swing clockwise about the gage 45, when the feeler 52 is again free to contact with the gage it will engage it at a point nearer the center of the spiral. This movement of the feeler 52 toward the center of the spiral re-

sults in the positioning of the controller rod to the right of its normal position, so that, after the spring 11 has been permitted by the cam 12 to draw the course pin feeler 9 into contact with the course pin determining the direction of the vessel and the cam 132 has acted to release the cam roll 133, thereby allowing the spring 89 to draw the controller 74 and with it the shaft 91 and cam 90 to the left, the controller 74 and the cam 90 will be held to the right of their normal position. Consequently, when the cam surfaces 99 and 100 come opposite the cam roll 101, the cam surface 99 by engaging the roll 101 will actuate the lever 102 to impart a clockwise movement to the rudder. This clockwise movement of the rudder acts to swing the vessel to the left and restore it to its chosen course. As the head of the vessel 20 swings to the left, when the feeler 52 is again in non-feeling position, it will swing in an anti-clockwise direction about the gage 45, so that, when the feeler 52 again contacts with the gage it will engage it at a 25 point of greater distance from the center of the spiral. As a result, when the controller rod 75 is again returned to its operative position, it is not so far to the right; and when the spring 89 is again permitted to move the controller to the left toward the compass, the controller and consequently the cam 90 will also assume a position farther to the left, thereby bringing the cam surface 100 into engagement with the cam roll 101 to actuate 30 the lever 102 to impart an anti-clockwise movement to the rudder 104. During the time the vessel is being restored to its pre-determined course, the feeler 52 constantly engages a point farther distant from the 35 center of the spiral until it finally reaches its normal position. These progressive movements of the feeler 52 result, through the mechanisms governed by it, in the rudder being restored to normal position in alinement with the vessel by successive increments. When the feeler 52 again contacts 40 with the part of the gage 45 corresponding to the course pin determining the course of the vessel, the controller rod 75 will be in normal position, and so also the controller 45 50 and the cam 90. At this time the rudder will be in alinement with the course of the vessel.

If the vessel deviates to the left of its course, when the feeler 52 contacts with the gage 45 on a fresh feeling movement, it will be at a point at a greater distance from the center of the spiral. This results in the controller rod 75 assuming a position to the left of its normal operative position. Consequently, the controller 74 and the cam 90 under the influence of the spring 89, are moved to the compass beyond their normal positions. The positioning of the cam 90 to the left of its normal position causes

the cam surface 100 to engage the cam roll 101 to actuate the lever 102 to impart an anti-clockwise movement to the rudder. As the vessel responds to the restoring movement of the rudder, the feeler 52 at each 70 feeling movement progressively engages the gage 45 at a point at a lesser distance from the center of the spiral, so that the controller rod 75 is progressively moved to the right to its normal position. The progressive movements of the controller rod to the right result in the cam surface 99 engaging the cam roll 101 at each rotation 75 of the cam 90 to actuate the lever 102 to impart a clockwise movement to the rudder 80 104 until it is restored to its normal position in alinement with the vessel.

Resetting mechanism.

If at any time the gage feeler 52 is in contact with the point 46 of the gage 45 and it is desired to lay out a course for the vessel the first leg of which is in the direction north and the next leg of which is to the left of the first leg, means are 90 automatically brought into operation to release the gage feeler from contact with the point 46 of the gage to permit the spring 57 to pull the gage feeler into contact with the point 47 so that the longest course pins 95 may be presented to the feeling movements of the course pin feeler. The means for automatically disengaging the feeler 52 from contact with any point on the gage 45 to permit the spring 57 to move the 100 feeler inwardly comprises a cam surface 194 formed on the periphery of the course-setting wheel 1. The cam surface 194 (Fig. 3) is adapted to engage a cam roll 195 pivoted on the lower end of an arm 196 of a bell-crank lever 197 fulcrumed in supports 198 and 199 rising from the platform 4. To the upper end of the other arm 200 of the lever 197 is pivoted one end of a link 201, the other end of which is pivoted on the 110 free end of the vertically disposed arm 203 of a bellcrank lever 204 fulcrumed in a support 205. The free end 206 of a horizontally disposed arm 207 of the lever 204 is in the form of a rod which is situated 115 under the upturned end 208 of a lever 209 pivotally mounted at 210 on the arm 66 of the bellcrank 54. The other end 211 of the lever 209 is disposed above the end 212 of a lever 213 pivoted at 214 on the arm 120 53 of the bellcrank 54. The other-end 216 of the lever 213 is disposed beneath the gage feeler 52. The above described construction is such that when the cam surface 194 engages the cam roll 195, and thereby 125 oscillates the bellcrank lever 197, the link 201 is moved to the left, viewing Fig. 2, thereby oscillating the bellcrank 204 and raising the rod 206. The upward movement of the rod 206 raises the end 208 of the lever 130

209, thereby depressing the end 211 of the lever 209. The downward movement of the end 211 depresses the end 212 of the lever 213, thereby raising the end 216 of the lever 213. The upward movement of the end 216 brings it into engagement with the under surface of the gage feeler 52, thereby releasing the feeler 52 from contact with the gage 45 and permitting the spring 57 to 10 swing the bellcrank 54 on its pivot until the feeler 52 is in contact with the point 47.

Automatic stopping device.

The course pin feeling lever 9 feels for 15 and contacts with each course pin twice a minute for six-minute periods. If during this time or any other predetermined time in which the course-setting mechanism is to operate, the vessel does not respond to its 20 rudder, the propelling power of the vessel is automatically shut off. The means for automatically discontinuing the propulsion of the vessel comprises an electric circuit having two terminals, a stationary terminal 25 165 (Fig. 3), and a vertically movable terminal 166. The stationary terminal 165 is arranged on the outer end of an arm 167 of a bracket 168 secured to the platform 4. The terminal 165 is disposed above the end 30 170 of an arm 171 (Fig. 1) of the lever 102. The movable terminal 166 is fixed on the upper end of a rod 172 mounted for vertical sliding movement in ears 173 and 174 projecting laterally from the bracket 168. A 35 spring 175, one end of which engages a collar 176 fixed on the rod 172 and the other end of which engages the under side of the upper ear 173, tends to depress the movable terminal 166 to keep it out of engagement 40 with the arm 171 and the stationary terminal 165. The movable terminal 166 is actuated to move toward the stationary terminal 165 in timed relation with the actuation of the course-setting wheel 1 and this 45 movement takes place just before the course-setting wheel is turned to present a new pin to the feeling movements of the feeler 9. If the vessel responds to its rudder and is headed on the course as determined by the 50 course pin engaged by the feeler 9 within the six-minute period or other predetermined period, the rudder actuating lever 102 will be in normal position and the end 170 of the arm 171 will be immediately under the 55 stationary terminal 165. Therefore, when the movable terminal 166 is actuated to move upward, it will contact with the arm 171, the electric circuit will not be closed, and the propelling power of the vessel will not 60 be shut off. The movable terminal is actuated from a cam groove 179 (Fig. 7) formed in one side of the cam 26. The cam groove 179 receives a cam roll 180 pivoted on the free end of an arm 181 of a bellcrank lever 65 182 fulcrumed on the pivot 31. Pivoted to

the free end of the other arm 183 of the bellcrank lever 182 is a link 184, the other end of which is pivoted to an arm 185 of a bellcrank lever 186 fulcrumed in supports 187 and 188 rising from the platform 4. The hub of the bellcrank 186 is greatly elongated and lies under the jack shafts 91 and 92. The arm 185 is at one end of the hub of the bellcrank lever 186 (Fig. 9), and at the other end is another arm 190 the outer 75 free end of which is connected with the rod 172 which supports the movable terminal. When the cam roll 180 is in the idle portion of the cam groove 179, the end of the arm 190 rests on the ear 174; but when the active 80 part of the cam groove 179 engages the cam roll 180, the arm 190 is actuated to impart an upward movement to the rod 172 and the movable terminal 166. In order to prevent the movable terminal 166 from contacting with the stationary terminal 165, in case the vessel should deviate from its chosen course just before the actuation of the movable terminal, the end 170 of the arm 171 is made wide enough so that, on the occurrence of any usual deviation of the vessel 90 from its course, the end 170 of the arm 171 will not be swung from under the stationary terminal 165. It is obvious that if the vessel deviates an unusual amount, the vessel ought 95 to be stopped, and in this case the arm 171 will be moved from under the stationary terminal, thereby permitting the movable terminal to strike it and close the circuit to shut off the engine or other motive power of 100 the vessel.

Predetermined course operation.

A plan of a predetermined course laid out for the purpose of illustrating the mode of 105 operation of the steering apparatus of the present invention in heading the vessel successively in different directions is shown in Fig. 10. The divisions of each leg of the course represent the distance that the vessel will travel in six minutes when the propeller shaft is making 1200 revolutions per minute, so that each division corresponds to the length of time each course pin is presented for feeling movement to the course 115 pin feeler; in other words, each division corresponds to one course pin. Fig. 11 represents the layout of the course-setting wheel 1 and the respective positions of pins of various lengths employed in order to direct 120 the vessel on the course as laid out in Fig. 10. In sailing the first leg of the predetermined course, the vessel is headed due north and its distance is such that when the propeller is turning 1200 revolutions per minute, the vessel will reach the end of the leg in twelve minutes. During these twelve 125 minutes, the course pin feeler 9 will have engaged at 30 second intervals the two first course pins of Fig. 11. It is obvious, of 130

course, that if the propeller makes less or more than 1200 revolutions per minute, it will require either a longer or a shorter time for the vessel to reach the end of leg 1; 5 but, inasmuch as the rotation of the course-setting wheel 1 and the feeling movements of the course pin feeler 9 are directly proportionate to the rate of rotation of the propeller shaft, the turning of course wheel 1 10 to present a new pin to the feeling movements of the feeler 9 will either be retarded or hastened, so that by the time the vessel reaches the end of leg 1, irrespective of the speed of the vessel, the course-setting wheel 15 will be turned to present pin 3 to the feeling movements of the course pin feeler. As shown in the layout of Fig. 11, the longest course pins are employed to direct the vessel due north; consequently, the gage feeler 52 20 contacts with the point 47 of the spiral gage, as shown in position 1 of Fig. 12. Now when the vessel reaches the end of the leg 1 and is to be headed in the direction of leg 2, which is northwest, that is, at an angle of 25 45° to the left of leg 1,—45° being $\frac{1}{8}$ of the total number of degrees,—the course pin 3 will be shorter than course pins 1 and 2 by $\frac{1}{8}$ of the distance between the heads of the longest and shortest course pins. After 30 the course-setting wheel 1 has been turned to present pin 3 to the feeling movements of feeler 9, on the next sequential action of the various cams, during which the rudder controller is swung into non-feeling position 35 and thereafter the active part of cam 12 passes the cam roll 13 to permit the spring 11 to pull the feeler 9 into contact with course pin 3, the end of the controller rod will be engaged by a point on the arcuate 40 surface of the controller 74 of greater radius than the point contacting the controller rod 75 when the course pins 1 and 2 were engaged by the feeler 9. Consequently, the cam 90 will not be returned to its normal 45 inoperative position by the spring 89, but will be held in such position by the locking device 135 that its cam surface 99 will engage the cam roll 101 to oscillate the lever 102 to impart a clockwise movement to the 50 rudder 104. Sufficient movement will be imparted to the rudder 104 to head the vessel in the direction of leg 2, and thereafter the rudder will be restored by successive increments of movement to its normal position in 55 alignment with the course of the vessel, by the cam surface 100 engaging the cam roll 101 to oscillate the cam actuating lever 102 in the opposite direction to impart an anti-clockwise movement to the rudder. After 60 the rudder has been moved to direct the vessel northwest, as the vessel swings to the left to the direction northwest, the gage feeler 52 is swung in an anti-clockwise direction about the gage 45 until, when the 65 vessel is headed northwest, the gage feeler

will contact with the gage, as shown in position 2 of Fig. 12. Leg 2 is composed of four divisions; consequently, four course pins are engaged by the course pin feeler 9 while the vessel is sailing on this leg. 70

Leg 3 lies in the direction north at an angle of 45° to the right of leg 2; consequently, when the vessel has completed leg 2, and at the termination of the last six-minute period of the four divisions of leg 75 2, the next course pin to be presented to the feeling movements of the feeler 9 is one of the longest course pins, that is, one longer than pins 3 to 6 inclusive by $\frac{1}{8}$ of the distance between the longest and the shortest course pins. When the rotation of cam 12 permits the spring 11 to draw the feeler 9 against the pin 7, and the active part of cam 132 passes cam roll 133, the spring 89 will act to draw the rudder controller 74 80 to the left toward the compass until a point on the arcuate surface of the controller of less radius is in contact with the controller rod 75, so that the controller is drawn farther to the left than the position it occupied when the vessel was sailing leg 2. 85 This movement of the controller to the left results in the engagement of the cam roll 101 by the cam surface 100 and the consequent turning of the rudder 104 in an anti-clockwise direction to swing the vessel until it heads due north. When the vessel has been headed north, the gage feeler 52 will have been swung about the spiral gage until it again contacts with the point 47, thereby 90 causing the controller rod 75 to be moved to the right until the rudder controller 74 restores the cam 90 to its normal inoperative position. As the cam 90 is being restored to this position, the cam surface 99 95 100 by engaging the cam roll 101 actuates the lever 102 to impart clockwise restoring movements to the rudder 104. Leg 3 is composed of four divisions; consequently, four course pins, 7 to 10 inclusive, are used 105 while the vessel is sailing on this leg. Leg 4 lies in the direction northwest, that is, at an angle of 45° to the left of leg 3; consequently, the various parts of the steering apparatus perform the same functions and 110 move through the same distances in swinging the vessel from leg 3 to leg 4 as they did in swinging the vessel from leg 1 to leg 2. Leg 4 being composed of four divisions, 115 four course pins, namely those numbered 120 from 11 to 14 inclusive, of the same lengths as pins 3 to 6, will be employed to direct and hold the vessel on this leg. While the vessel is headed on leg 4, the gage feeler will engage the gage as shown in position 4, 125 Fig. 12, which is identical with the position occupied by the gage feeler while the vessel was sailing leg 2, as shown by position 2. Leg 5 lies in the direction west, that is, to the left of leg 4 at an angle of 45°; ac- 130

cordingly, the course pins necessary to direct the vessel in the direction of leg 5 must be $\frac{1}{8}$ of the distance between the longest and the shortest course pins shorter than 5 the course pins employed to direct the vessel on leg 4. The various parts of the steering apparatus perform the same functions in swinging the vessel from leg 4 to leg 5 as they performed in swinging the vessel from 10 leg 1 to leg 2. When the vessel is headed in the direction of course 5, the gage feeler 52 will be positioned as shown in position 5 of Fig. 12. The increase of the curve of the spiral at the point where the gage feeler 15 contacts with the gage is $\frac{1}{4}$ of the distance between the points 47 and 46, so that the course pins contacted with by the course pin feeler 9 are $\frac{1}{4}$ shorter than the longest course pins. Leg 5 being composed of six, 20 six-minute divisions, six course pins, namely those numbered from 15 to 20 inclusive, will be employed in holding the vessel on leg 5.

Leg 6 lies in the direction south and so 25 is at an angle of 90° to the left of leg 5. In order to direct the vessel in the direction of leg 6, therefore, it is necessary to employ course pins 21 to 25, which are $\frac{1}{4}$ shorter than those employed in directing the 30 vessel on leg 5, that is, course pins 21 to 25 occupy a position $\frac{1}{2}$ the distance between the longest and shortest course pins. When the vessel is headed in the direction of leg 6, the gage feeler 52 will contact with a 35 point on the gage where the increase of the spiral is $\frac{1}{2}$ the distance between the points 47 and 46, as shown in position 6 of Fig. 12. Since the vessel swung through an angle of 90° in passing from leg 5 to leg 40 6, it was necessary that the gage feeler should also swing through an angle of 90° . The movements imparted to the rudder controlling and actuating mechanisms in changing the direction of the vessel from 45 leg 5 to leg 6, are the same as those imparted to them in changing the vessel from leg 4 to leg 5, except that each part moves through twice the distance. Inasmuch as leg 6 is composed of five, six-minute divisions, five course pins are employed.

The direction of leg 7 differing from the direction of leg 6 by an angle of 45° to the left, and leg 8 differing from leg 7 by an angle of 45° to the left, in order to direct 55 the vessel in the direction of leg 7 the course pins employed namely 26 to 30 inclusive, will be $\frac{1}{4}$ shorter than those used in directing the vessel on leg 6. And in directing the vessel on leg 8, the course pins, namely 60 those numbered 30 to 33 inclusive, will be $\frac{1}{4}$ shorter than those used in directing the vessel on leg 7. Leg 7 consisting of five, six-minute divisions, five course pins will be contacted with by the course pin feeler 65 while the vessel is sailing on this leg. Leg

8 consisting of three, six-minute spaces, three course pins will be contacted with by the course pin feeler while the vessel is sailing on this leg. As the vessel is headed successively in the direction of leg 7 and in the 70 direction of leg 8, the gage feeler 52 will successively contact with the gage, as shown in positions 7 and 8 of Fig. 12.

Leg 9 of the predetermined course is to the left of leg 8 at an angle of 90° . Leg 9 75 lies in the direction north, namely the direction of leg 1. To change the vessel from leg 8, to leg 9, that is, to swing its head through 90° , it is necessary to employ course pins 34 and 35, which are $\frac{1}{4}$ shorter than the 80 course pins of leg 8. Since in passing from leg 8 to leg 9 the head of the vessel is swung through 90° , the new position of the gage feeler 52 will be 90° removed from the position shown in position 9. The course pin 85 feeler 9 now engaging the shortest course pins, the gage feeler 52 is in contact with a point on the gage corresponding thereto, namely the point 46, as shown in position 9. Thus, it is apparent that when either the 90 longest or the shortest course pins are contacted with by the course pin feeler, the vessel is headed in the same direction. Leg 9 consisting of two, six-minute spaces, two 95 course pins are used.

Leg 10 being at an angle of 90° to the right of leg 9, it is necessary to use course pins which will cause an anti-clockwise movement to be imparted to the rudder, that is, the course pins used must be such as to cause the controller rod 75 to be positioned to the right of the position held by it while the vessel was sailing on leg 9, and since the vessel must swing through an angle of 90° so that the gage feeler 52 will 100 be swung from its position shown in position 9 to the position shown in position 10 of Fig. 12, and at the same time must move inwardly toward the center of the spiral a distance equal to $\frac{1}{4}$ the distance between the points 46 and 47, the course pins employed in directing the vessel on leg 10 must be 36 and 37, that is, $\frac{1}{4}$ longer than the pins employed in directing the vessel on leg 9. For 105 the same reasons, to direct the vessel on leg 11, which lies to the right at an angle of 90° to leg 10, it is necessary to employ pins 38, 39 and 40 which are $\frac{1}{4}$ longer than course pins 36 and 37. When the vessel is headed in the direction of leg 11, the gage feeler 52 will contact with the gage 45 at the point indicated in position 11, which is the same point indicated in position 6 when the vessel was sailing on leg 6. At the end of the 110 six-minute period during which the course pin feeler 9 contacts at its regular intervals with course pin 40, the vessel will have completed its predetermined course. If, now, it is desired that the vessel should again be 115 headed in the direction north, the course- 120 pin feeler 9 will contact with the gage 45 at the point indicated in position 12, which is the same point indicated in position 7 when the vessel was sailing on leg 7. At the end of the 125 six-minute period during which the course pin feeler 9 contacts at its regular intervals with course pin 40, the vessel will have completed its predetermined course. If, now, it is desired that the vessel should again be 130 headed in the direction north, the course-

setting wheel 1 will be turned to present pin 41, that is, one of the shortest pins to the feeling movements of the course pin feeler.

It will be observed that whether the vessel is being changed from one leg to another of a predetermined course, or whether the vessel is being restored to its given course upon a deviation therefrom, in the sequential action of the various mechanisms 10 composing the steering apparatus, the course pin feeler 9 is first brought into engagement with the course pin determining the direction in which the vessel is to sail and that, thereafter, the rudder controller is 15 brought into contact with the controller rod.

It is obvious that the invention is not limited to the particular form in which it is shown and described, since it contemplates embodiment in any form in which the principles herein described may be carried into 20 operation and falling within the scope of the appended claims.

The nature and scope of the present invention having been indicated and an apparatus embodying the several features of the invention in their preferred form having been specifically described, what is claimed 25 is:—

1. A steering apparatus having, in combination, a moving object, a guiding device, a compass, means operatively connected with the compass for directing and holding the object upon a predetermined course consisting of a number of legs, one or more of 30 which lie in a left hand direction and one or more of which lie in a right hand direction from the preceding legs.

2. A steering apparatus having, in combination, a moving object, a guiding device, a compass, a course setting device, and means connected with the guiding device and the course setting device for heading and holding the object upon a predetermined course consisting of a number of legs, 45 one or more of which lie in a left hand direction and one or more of which lie in a right hand direction from the preceding legs.

3. A steering apparatus having, in combination, a moving body, a guiding device, a compass, a course setting device, and means for actuating the guiding device and controlled in its operations by the compass and by the course setting device for changing 55 the direction in which the object is proceeding so that the object will be turned both to the left hand and to the right hand during the progress of the object upon a predetermined course.

4. A steering apparatus having, in combination, a moving body, a guiding device, means upon which a predetermined course consisting of one or more legs may be laid out, said means comprising a series of course 60 pins of lengths varying proportionately to

the angular space between the course legs, a course pin feeler arranged to constantly and intermittently contact with the course pins, means for moving the pins to present different pins to the course pin feeler, and connections between the course pin feeler and the guiding device for directing the object as determined by the length of the course pin engaged by the course pin feeler.

5. A steering apparatus having, in combination, a moving object, a guiding device, means upon which there may be laid out a predetermined course consisting of one or more legs of which the succeeding legs may be either directed to the right or to the left 70 of the preceding legs, said means comprising a series of points spaced apart proportionately to the angular space between the course legs respectively, and a compass controlled means for actuating the guiding device and adapted to be moved through the spaces separating the points, the amount of actuation of the guiding device depending upon the space traversed by the guiding device actuating means.

6. A steering apparatus having, in combination, a moving object, a guiding device, a course setting device upon which a predetermined course for the moving object may be laid out comprising course pins of lengths 75 corresponding to the directions in which the object is to be headed, a course pin feeler, means connected with the course pin feeler and with the guiding device for actuating the latter to head the object in the same 80 direction when the course pin feeler engages either the shortest or longest course pins.

7. A steering apparatus having, in combination, a moving object, a guiding device, a course-setting wheel, course-setting pins of lengths 95 corresponding to the direction in which the object is to move, a course pin feeler, and connections between the course pin feeler and the guiding device for turning the guiding device to head the object in the direction as determined by the course pin with which the course pin feeler is in engagement.

8. A moving object having, in combination, a compass, a guiding device, and a steering apparatus comprising a series of course pins of lengths corresponding respectively to the directions in which the object is to be headed, a course pin feeler, 115 and means controlled thereby and adapted to be brought into operative connection with the compass for actuating the guiding device to head the object in the direction as determined by the course pin with which the course pin feeler is in engagement.

9. A moving object having, in combination, a guiding device, and a steering apparatus for actuating the guiding device comprising a series of course setting pins of 120

lengths corresponding respectively to the directions in which the object is to be headed, a course pin feeler arranged to intermittently move into and out of contact with the 5 course pins, and connections between the course pin feeler and the guiding device.

10. A steering apparatus having, in combination, a moving object, a guiding device, a compass, a spiral gage connected with the 10 compass having points corresponding to the points of the compass, a gage feeler adapted to contact with different points on the gage according to the various directions respectively in which the object is headed, and 15 means controlled by the gage feeler for actuating the guiding device for restoring the object to the direction in which it was headed upon a deviation therefrom.

11. A steering apparatus having, in combination, a moving object, a guiding device, a compass, a spiral gage on the compass having points corresponding to the points of the compass, a course setting device comprising a series of pins of lengths proportionate respectively to the radial distance the points on the spiral gage are from the center of the compass, a gage feeler for contacting with the gage, a course pin feeler, and means controlled by the gage feeler and 30 by the course pin feeler for actuating the guiding device.

12. A steering apparatus having, in combination, a moving object, a compass, a guiding device, a course setting device, 35 means operatively connected with the course setting device, and with the compass for actuating the guiding device to head the object in a given direction for a predetermined length of time and for automatically heading 40 the object in new directions both to the left hand and to the right hand of the given direction while the object is proceeding upon a predetermined course.

13. A moving object having, in combination, a compass, a guiding device, and a steering apparatus comprising, a course-setting wheel, course pins mounted thereon of lengths corresponding to the direction in which the object is to be headed, a course 50 pin feeler, and means controlled thereby for actuating the guiding device to head the object in the direction as determined by the course pin with which the course pin feeler is in engagement.

55. 14. A steering apparatus having, in combination, a moving object, a guiding device, a compass, means for directing the object on a predetermined course of one or more legs, a spiral gage connected with the compass, a gage feeler, means for actuating the guiding device, and means governed as to its operative position by the point on the spiral gage contacted with by the gage feeler for controlling the amount of movement to be imparted to the guiding device

by its actuating means for restoring the object to its predetermined course upon a deviation therefrom.

15. A steering apparatus having, in combination, a moving object, a guiding device, 70 a compass, a course-setting wheel having course-setting pins of lengths corresponding to the direction in which the object is to be headed, a course pin feeler, a spiral gage connected with the compass, a gage feeler, 75 means for actuating the guiding device, and means governed as to its operative position by the course pin engaged by the course pin feeler and the point on the spiral gage contacted with by the gage feeler for controlling the amount of movement to be imparted to the guiding device by its actuating means.

16. A steering apparatus having, in combination, a moving object, a guiding device, 85 a compass, means for setting the object on a predetermined course of one or more legs, means for actuating the guiding device, means for controlling the amount of movement imparted to the guiding device by its 90 actuating means, and means for detecting the amount the object deviates from its predetermined course comprising a spiral gage connected with the compass, a gage feeler, 95 and a controller rod.

17. A steering apparatus having, in combination, a moving object, a guiding device, a compass, means for setting the object on a predetermined course of one or more legs comprising, a course-setting wheel having 100 course-setting pins of lengths corresponding to the direction in which the object is to be headed, a course pin feeler, means for detecting the amount the object deviates from its predetermined course comprising, 105 a spiral gage connected with the compass, a gage feeler, and a controller rod governed as to its operative position by the point on the spiral gage contacted with by the gage feeler, means for actuating the guiding device, 110 and means for controlling the amount of movement to be imparted to the guiding device by its actuating means comprising a rudder controller connected with the course pin feeler and adapted to be brought 115 into engagement with the controller rod.

18. A steering apparatus having, in combination, a moving object, means for propelling the object, a guiding device, means for directing the object on a predetermined course of one or more legs, means controlled by the course-setting means for actuating the guiding device to direct the object on the leg of the course as determined by the course-setting means, and a stopping device 120 for discontinuing the propelling means if, after the lapse of a predetermined time, the moving object has not responded to its guiding device.

19. A steering apparatus having, in com- 130

bination; a moving object, a guiding device, a compass, a spiral gage on the compass having points corresponding to the points of the compass, a gage feeler, and means 5 for actuating the guiding device to head the object in the same direction when the gage feeler contacts with the points on the spiral gage having the greatest and the least radial distance from the center of the 10 compass.

20. A steering apparatus having, in combination, a moving object, a guiding device, a compass, a spiral gage on the compass, a gage feeler, means operatively connected 15 with the gage feeler for actuating the guiding device to head the object in the same direction when the gage feeler contacts with the points on the gage at the greatest and least radial distance from the center 20 of the compass, and means for moving the gage feeler from contact with the outermost point on the gage into contact with the innermost point thereon.

21. A steering apparatus having, in com-

bination; a moving object, a guiding device, 25 means for directing the object upon a predetermined course consisting of one or more legs comprising, a course-setting wheel and course pins of lengths corresponding to the directions in which the object is to move on its predetermined course, means for detecting the amount the object deviates from its predetermined course comprising, a compass, a spiral gage on the compass, and a gage feeler, the spiral gage 30 and gage feeler being constructed and arranged so that, when the longest course pins are in operative position, the innermost point on the spiral gage is engaged by the gage feeler, and when the shortest 35 course pins are in operative position, the outermost point on the spiral gage is contacted with by the gage feeler, and means for disengaging the gage feeler from contact with the outermost point on the spiral 40 gage to permit it to be brought into engagement with the innermost point thereon.

ERASTUS. E. WINKLEY.
